UNITED STATES PATENT OFFICE.

GEORGE LAWSON BALLARD, OF NORRISTOWN, PENNSYLVANIA, ASSIGNOR TO WILD-MAN MFG. CO., A CORPORATION OF PENNSYLVANIA.

STRIPING MECHANISM FOR KNITTING-MACHINES.

1,255,124.

Specification of Letters Patent.

Patented Feb. 5, 1918.

Application filed May 22, 1914. Serial No. 840,378.

To all whom it may concern:

Be it known that I, GEORGE LAWSON BALLARD, a subject of the King of Great Britain, residing at Norristown, Pa., have invented certain new and useful Improvements in Striping Mechanism for Knitting-Machines, of which the following is a specification.

The invention consists in the features and combination and arrangement of parts hereinafter described and particularly referred to in the appended claims.

In the accompanying drawings—

Figure 1 is a front view of so much of a circular machine as is necessary to a clear understanding of my invention which is shown applied thereto. The yarn changing devices are shown slightly displaced in position for convenience of illustration.

Fig. 2 is a rear view of part of the controlling mechanism.

Fig. 3 is a view of a detail.

Fig. 4 is a plan view of Fig. 1 with the upper structure and knitting head partly broken away and showing a portion of the lower structure.

Fig. 5 is a detail side view.

Fig. 6 a detail plan view.

Fig. 7 a side view.

Fig. 8 a detail front view of one of the stiper attachments.

Fig. 9 is a view of a detail.

While features of my invention may be applied to machines of various types and in various ways, in the particular example of my invention herein disclosed, I show the invention as applied to a machine of the rotary needle cylinder type, and while my invention may be applied to machines for making various articles and tubular fabrics of various diameters, in the particular form shown it is illustrated in connection with a body machine for making, for instance, sweaters.

In the drawings 1 indicates the rotary needle cylinder, 2 the cam cylinder. Disposed at different points, say four in number, about the needle cylinder and fixed in relation thereto are the stripers. Each stiper comprises a pair of yarn feed fingers consisting of arms w' and r' pivoted at 3 and pressed by springs 3' to their low positions for feeding their yarn to the needles. The inner ends of these yarn feed fingers have

curved upwardly extending portions which are each provided with two guide eyes or openings, the yarn being led first through the upper opening or eye 4 and thence inwardly through the lower eye 4' to the needles. The yarn is directed to the feed fingers by a guide 5 one for each stiper, only one however, being shown in Fig. 1. These guides are fixed on the dial cap 6, each guide having two openings, one for say a white yarn w and the other for a red yarn r . These yarn guides extend down to a point about on a level with the upper ends of the yarn feed fingers when the latter are in their lowered positions and they are provided with a piece of felt or fibrous material 7, 70 against and under the lower edge of which the yarn is drawn when either yarn finger is lifted out of work, the finger when so lifted having its upper eye occupying a position some distance above the lower end of the yarn guide so that slack will be drawn when the yarn finger is raised to provide the necessary excess or slack when this yarn end is introduced to the needles again. In so drawing this slack the felt, wool or other fibrous material places a drag or restraint on the yarn to prevent the yarn feed finger drawing off too much. The yarn fingers may be raised to withdraw their yarn from the needles by various means but in the particular construction shown controllers or cams 8 are used one for each stiper attachment.

These controllers are fixed to rock shafts 9, operated each by an arm 10 at its upper end 90 connected by a link 11 with the disk or plate 12 arranged to turn about the dial post 13, and when so turned this disk will operate all of the links 11 and these will operate their respective arms 10 and cause the cams or controllers to be operated, as will be more fully described hereinafter. These cams or controllers comprise depending portions provided with inclined lower edges which work upon the outer ends of the arms carrying the yarn feed fingers. When the cam portion is turned from central position either way it will ride over either one or the other of the said arms at the outer end thereof and tip the same down, thus lifting the inner end 105 and raising the yarn feed finger, together with its yarn, from the needles, this action taking place against the power of the spring

3'. When the cam shaped controller is moved from over either yarn finger arm this arm will be lowered by its spring to put the yarn carried thereby in work.

5 Each striper also comprises a yarn cutter and clamp. The cutter consists of a fixed shear blade 14 and a movable blade 15, the latter being pivotally mounted at 16 and being operated by an arm 17 attached to its 10 pivot or shaft.

This arm is connected by a link 17' with an arm 18 of a hollow sleeve 19 turning about the rock shaft 9 above mentioned. This sleeve has an arm 20 at its upper end 15 connected by a link 21 with a second disk 22 also mounted to turn about the dial post. When this disk is operated the movable shear blades (four in the example shown) will be operated to open or close as the case 20 may be.

Associated with each yarn cutter is a clamp for holding the end of the yarn when raised out of work and severed by the cutter, and while this may be variously arranged and constructed, in the particular form of the invention shown it consists of a spring plate 23 held by screws 24 and overlying the cutter blades.

Each striper has a bracket 25 for supporting the various parts thereof above described, and each bracket is held on a post 26 by a set screw 27, the post being supported in the usual cam ring.

For operating the central disks and therefore by operating the yarn feed fingers and yarn cutters, I employ contact means located in part on the rotary portion of the machine and in part on the fixed portion. These contact devices may be variously constructed 40 and arranged according to the particular type of machine to which my invention is applied, but in the particular construction shown I employ a pair of star wheels 28, 29 on shafts or drums 30, mounted in a standard 45 31, fixed to the stationary base ring 32 of the machine, this ring, as in usual practice supporting by standards 33, the fixed base ring 34 of the knitting head. The star wheel 28 has its shaft or drum connected with a rod 35 by a pin 36 which is arranged eccentric to the center of the shaft or drum. The upper end of this rod is connected by a bell crank lever 37 and a link 38 with the upper 50 central disk 12 and when these parts are operated, as will be presently described, the central disk is turned and through the several links 11 the controllers or cams 8 are operated.

The bell crank lever is pivoted to a collar 39 fixed on one of the posts 40 which support the usual upper yoke 41, which in turn supports the dial post 13. The shaft or drum of the star wheel 29 has a cam 42 formed therewith or fixed thereto, and this may be 55 formed by flattening the sides of the exten-

sion of the said shaft or drum. This cam operates upon a lever 43, Figs. 2 and 4, which lever is pivoted at 44 to the standard 31 and is pressed upwardly by a spring 45. It has a rod 46 pivotally connected thereto, which 70 rod is connected through a bell crank lever 47, pivoted on the collar 39, and a link 48 with the lower one 22 of the central disks so that when this star 29 is turned the rod 46 will be operated and through the connection 75 described the links 21 will all be operated simultaneously to operate the movable shear blades. The parts are so arranged that when the cam 42 depresses the lever 43 the shear blades 15 will all be closed to cut the yarn 80 which has just been raised out of work and when the low flat side of the cam allows the lever 43 to rise under the action of its spring 45 all of the shear blades will be opened, this happening when the yarn is to be introduced 85 to the needles again.

It may be mentioned here that the movable shear blades act in connection with the spring clamp to hold the yarn, said blade at the time of cutting the yarn serving to push 90 the end under the spring clamp plate to be held thereby, and therefore upon the opening movement of the shear blade the yarn end which has been held thereby in connection with the spring clamp will be released, this taking place as above described 95 at the time the yarn is thrown into work.

The star wheels have each four arms or points, two of these are narrow as at 'b' and the other two are wide as at 'c.'

For operating the star wheels (a quarter turn at each action) pins 50, 51 are provided on the rotary take-up ring 52, this ring rotating with the needle cylinder in the direction of the arrow 'x' in Fig. 4. This ring 105 is connected with the cylinder to rotate therewith by the standards or posts 53, which posts as in usual practice, furnish the supports for the take up rolls 54, Fig. 1. The pin 50 is slidably mounted in a standard or 110 post 55 fixed to the revolving take-up ring 52 while the pin 51 is fixed by a screw 56 in a standard 57 carried by said revolving take-up ring. The sliding pin 50 is operated by a lever 58 pivoted to the pin 51 at 59, 115 said lever being in turn operated by the pin 60 slidably mounted in a post 61 also supported on the revolving take-up ring. A cam 62 is vertically adjustable so as to locate its edge 62' to be either in the plane of the 120 pin 60 for pushing it inwardly as the pin rides upon the inner surface of said cam or to be in the plane of travel of the pin 50 to push it inwardly. The cam is guided in its vertical movements by a post 63 and a pin 125 64 fixed to and extending up from the fixed base ring 32 and it is adjusted vertically by connections to a suitable pattern mechanism and while this may be of various forms, in the particular form shown these connections 130

consist of a rod 65, a lever 66 pivoted at 67 and operated by pins 68 which may be set at different points according to the pattern desired on a pattern wheel 69, these pins being 5 in the form of screws adapted to be screwed into or removed from holes in the wheel indicated at 70 to change the pattern. The cam is moved down in line with the pin 60 by the pattern lever and the connection described and it is moved to its upper limit to be in line with the pin 50 by a spring 71.

The machine is shown, Figs. 1 and 4, with the white yarn *w* in work and the red yarn *r* out of work, the yarn finger *r'* having been 15 lifted by the controller or cam 8 riding on the outer or tail portion of said arm and tipping its inner end upwardly. The pin 50 which operates only upon the narrow teeth of the star wheel, is in its innermost 20 position, having been moved to this position by the cam edge 62'. The pin 60 is in its outermost position but being in a low plane it will not be operated by the cam edge 62' which is now in its uppermost position. 25 Furthermore, it will be noticed that the star wheels have been left in such position that their narrow arms are lowermost and as the pin 50 is at its inward limit it will pass these narrow arms without contacting there- 30 with. Again it will be observed that the fixed pin 51 being only long enough to reach the wide arms *e*, this pin will likewise be ineffective in the position in which the machine is shown because the wide arms or 35 teeth of the star wheels are above the plane of movement of this fixed pin. The pin 60, as before stated, travels in a path below that of the star wheels and has no effect thereon, the function of this pin, when operated by 40 the cam 62', being to operate the lever 58 to project the pin 50 outwardly to operate the star wheels by striking their narrow arms or teeth. Supposing the yarns are to be 45 changed by withdrawing the white and introducing the red yarn, the pattern mechanism will move the cam 62 down so that its edge 62' will be in the plane of travel of the pin 60. As the pin 60 comes around it rides upon the cam edge 62' and is moved 50 inwardly and through the lever 58, operates to throw the high long pin 50 outwardly, which high pin is long enough, as above stated, to reach the narrow teeth of the star wheels when so moved outwardly.

55 On giving the first star wheel 28 a quarter turn by contact of the long pin 50 the crank shaft of the star wheel is given a quarter turn, lifting the rod 35 half way up and this through the upper central disk 12 moves 60 the controller 8 to central position which allows the red yarn guide *r* to fall.

The high long pin 50 after operating the first star wheel and having lowered the red yarn guide *r*, passes on to the second star 65 wheel 29 and operates this a quarter turn by

engaging with the narrow tooth thereof. This operates through rod 46 to open the cutter or shear blade by swinging the movable blade inwardly. These two actions, i. e. lowering the red yarn finger *r'* and 70 opening the shear blade, releases the red yarn *r* from the clamp 23 and places it in work.

As soon as this opening of the shear blade has been completed the middle pin 51, which 75 is shorter than the pin 50, strikes the broad tooth of the first star wheel 28 and gives this another quarter turn which has the effect of throwing out or upwardly the white yarn guide *w* with the result that this now enters 80 the shears to be severed and clamped. The middle pin 51 now contacts with the broad tooth of the second star wheel 29 and gives it another quarter turn with the result that the shears are closed and the white thread is 85 severed and its end clamped by the thin spring plate 23. The red thread is now in work to make the stripe and the star wheels are left in the position shown in the figure, with their narrow teeth down in the path of 90 the pins and if changing of the yarns is to continue then as the machine continues the long pin 50 will operate the star wheels again by engaging their narrow teeth, and this will throw the white yarn carrier down 95 to introduce the white yarn and the red yarn carrier will be thrown up to put it out of work when the middle pin operates on the wide tooth of the star wheel 28 and the shears will be opened and closed as 100 above described, together with the clamp.

The pin 50 may now be rendered inoperative for the continued use of the white yarn, supposing the body of the fabric to be white, therefore the cam 62 is raised to the 105 position shown to push inwardly the pin 50 so that it will not operate against the narrow teeth of the star wheels and further as the fixed middle pin 51 is not long enough to reach out to the narrow teeth but long 110 enough only to reach the broad teeth which are now above the plane of the pin, and further as the low pin 60 does not operate the star wheels at all, the machine will continue knitting white or the body fabric as long 115 as the parts are in the position shown.

When the cam 62 operates the pin 50 inwardly and the pin 60 outwardly it places said pin 60 in position to be operated by the cam 62 if this should be lowered and when 120 so operated the pin 60 will be forced inwardly and through the lever 58 the pin 50 will be forced outwardly and thus be in position to operate upon the narrow teeth of the star wheels for again changing the yarn 125 to red yarn. The cam 62 having been lowered from the position shown into the plane of the pin 60 and having operated said pin to make the pin 50 effective on the star wheel remains in this position so long as changes 130

are to be made in the colors. Thus the striping effect can be continued.

In operating the star wheels by pin 50 the broad teeth of said star wheels are lowered into the plane of the fixed pin 51 which now operates them.

The sequence of operations at the stripes is to first lower the inoperative yarn finger by moving the controller 8 to neutral position, next open the shears to receive the other yarn, (these operations being performed by pin 50 acting on the two star wheels in succession) next lift the other yarn guide out of operation (by throwing the controller 8 in the opposite direction or rather in the same direction which it had when returning to neutral position,) and fourth close the shears, these last two operations being performed by the pin 51 acting 20 in succession on the star wheels.

With the narrow and broad tooth star wheels the parts will be controlled to work in time, for instance, supposing one of the star wheels has been turned accidentally so 25 that its broad tooth is lowermost while the narrow tooth is lowermost on the adjacent star wheel. This, if it be star wheel 28 which is out of time, would cause two ends or yarns to be in work at once, but this condition would not continue because the star 30 wheel would be immediately turned by contact of one of the pins with its broad tooth and thus one yarn would be thrown out and the other left in.

When both yarns are in, this condition will exist only during the distance between pins 50 and 51. In other words, if either star wheel gets out of position the fixed pin 51, operating on the broad tooth of either 40 wheel, will bring it into the position shown with the narrow teeth lowermost.

I have shown the knitting head only diagrammatically. Its cams may be operated in various ways.

It will be observed that in the present 45 form of machine all the stripers are operated simultaneously to change yarns, and while this and the means for doing this form a part of my invention, said invention in some of its features and aspects is not limited in this regard.

Any suitable detent means may be provided for the star wheel. I have indicated in Fig. 2 spring pressed detents 72 adapted 55 to engage recesses 73, Fig. 3, in the shafts of the star wheels.

I claim;—

1. In combination with a circular knitting machine, a stiper comprising a pair of yarn feed fingers movable to and from operative position, a yarn cutter, a controller for operating the yarn fingers, a vertical shaft and a sleeve concentric thereto, one of said concentric parts being connected with the controller and the other of said concentric parts

being connected with the cutter, and connections for operating said concentric parts to cause the controller to operate the yarn fingers alternately and to operate the cutter, substantially as described. 70

2. In combination with a circular knitting machine, a stiper comprising two pivotally mounted yarn feed fingers moving in vertical planes, a cutter and clamp for the yarn, said cutter comprising a pivoted shear 75 blade, a controller for operating the fingers, a vertical shaft carrying said controller, a sleeve mounted on the vertical shaft, connections to the shaft and sleeve for operating them and a connection from the sleeve 80 to the movable shear blade for operating the same.

3. In combination in a circular rib knitting machine, a cylinder and dial, a dial post, a plurality of yarn changing means 85 each comprising a pair of yarn fingers and a yarn cutter, a pair of star wheels on the fixed frame, one for all of the pairs of yarn fingers and one for all the cutters, two contacts on and traveling with a moving part of the machine to operate in succession upon each of the star wheels, a cam for determining the times of action of the contacts upon the star wheels, pattern mechanism for moving the cam, connections leading from one star 90 wheel to all the pairs of yarn fingers at the different feeds to move one yarn finger into work before the other yarn finger is withdrawn from work, and for then operating said other yarn finger to inoperative position, and connections from the other star 100 wheel to each of the cutters at the different feeds for opening all the cutters on one operation of the star wheel and for closing all the cutters upon a second operation of the star wheel, said connections including a pair of disks one above the other supported at a point above the dial cap and moving about the dial post, substantially as described. 110

4. In combination in a circular knitting machine, a plurality of stripers, each including a pair of yarn fingers and a yarn cutter and clamp, a member movable circumferentially and about the axis of the knitting 115 head, connections from said member to the yarn fingers for changing them, a second member movable circumferentially and about the axis of the knitting head, connections from said second member to the cutters, a star wheel for operating the said first member by successive steps and in one direction for each yarn changing action, a star wheel for operating the second member first in one direction and then in the other for the yarn 120 severing action, and means for operating each star wheel twice for each yarn changing action substantially as described. 125

5. In combination in a circular knitting machine, a plurality of stripers, each com- 130

prising two pivotally mounted yarn feed fingers movable in a vertical plane, and a yarn cutter and clamp, an oscillating controller movable in a horizontal plane and 5 having a cam action on said feed fingers for changing their relative positions, a circumferentially movable member arranged about the axis of the knitting head, connections therefrom to the oscillating controller, 10 a second circumferentially movable member arranged about the axis of the knitting head, connections from said second member to the yarn cutters to move them simultaneously, said connections including a member oscillating about the axis of the oscillating controller, and means for operating 15 said circumferentially movable members, said means operating the first circumferentially movable member step by step first in one direction and then in the other for performing successive yarn changing action and operating the second circumferentially movable member first in one direction and then in the other for performing the cutting operations, substantially as described.

6. In combination a rotary needle cylinder, a yarn changer comprising a pair of yarn fingers and a yarn cutter, a controller swinging about a vertical axis, for operating the yarn fingers, a member arranged concentric with and turnable about the axis of the controller, a connection from said member to the yarn cutter, a pair of members rotatable about the axis of the needle

cylinder, a connection between one of said members and the controller, a connection between the other of said members and the concentric member which operates the cutter, a pair of star wheels on the fixed frame, a connection from one star wheel to one of the pair of rotary members, a connection from the other star wheel to the other one of the pair of rotary members, a pair of contacts traveling with the needle cylinder for operating each of the star wheels twice 45 during the passage of the contacts past the star wheels, to move the controller step by step and to open and close the yarn cutter, and pattern controlled cam means controlling the action of the contacts, substantially 50 as described.

7. In combination in a circular knitting machine, a plurality of stripers, each including a pair of yarn changers and a yarn cutter, a rotary motion transmitting device 55 connected with the yarn changers, a second rotary motion transmitting device connected with the yarn cutter, and means for operating said devices, said devices being self correcting to keep in time should their relative 60 time of operation be disturbed.

In testimony whereof, I affix my signature in presence of two witnesses.

GEORGE LAWSON BALLARD.
